UNITED STATES PATENT OFFICE.

METHOLD F. SITTA, OF CHICAGO, ILLINOIS.

TYPEWRITER-DESK.

1,370,373.

Specification of Letters Patent. Patented Mar. 1, 1921.

Application filed September 20, 1920. Serial No. 411,433.

To all whom it may concern:

Be it known that I, METHOLD F. SITTA, a citizen of the United States, residing at Chicago, in the county of Cook and State of Illinois, have invented new and useful Improvements in Typewriter-Desks, of which the following is a specification.

This invention relates to improvements in typewriter desks, and is in many respects an improvement on the device shown in my co-pending application Serial No. 371,607, filed April 6th, 1920.

One of the principal objects of the invention is to provide new and improved means for lifting the typewriter table from a folded position to a horizontal position.

Another object is to provide means for maintaining the table in raised position.

Another object is to provide a new and improved track system for such a device.

Another object is to provide a locking means for maintaining the table in its folded or inoperative position.

Another object is to provide a trigger for releasing said table from said locking means.

Other objects will appear from the following description and claims, and all of these objects are accomplished by the mechanism shown in the accompanying drawing consisting of one sheet, in which:—

Figure 1 is a front-to-rear vertical section of a desk embodying my improvements, the typewriter table being shown in its folded or concealed condition.

Fig. 2 is a fragmentary view of the same, showing the table in its elevated position.

Fig. 3 is a detail sectional view taken vertically through one of the track members and the adjacent parts.

Fig. 4 is a top plan view of the track and adjacent parts on one side of the desk.

Like characters of reference refer to like parts in all views.

This invention contemplates the provision of a means which may be attached to an ordinary desk between the inner vertical walls thereof and which may be operated in the same manner as a drawer of the desk to bring a concealed typewriter into operative condition.

Referring more particularly to the drawings, 1 represents a desk, and 2 represents one of the inner walls thereof. To this inner wall are secured pivot members 3 upon each of which is rotatably mounted a roller

4. These rollers 4 are adapted to work in the upper channel of an S-shaped track member 5. In the lower channel of member 5 are rollers 6, each of which is mounted to 60 rotate upon a pivot pin 7. The pivot pins 7 are securely attached to a bar 8. The channels may be partly or wholly closed at the ends to prevent escape of the rollers. This mechanism is duplicated upon the opposing 65 inner wall of the desk, as will be readily understood.

A member or board 9 is provided and normally is in the position shown in Fig. 1, in which it gives the appearance of being a 70 drawer of the desk, and conceals a typewriter indicated by the dotted lines at 10. The typewriter is secured to the member 9 but may be slidably secured so as to be capable of moving forward on the member 9 when 75 the latter is raised to the position shown in Fig. 2. The board 9 is pivotally secured at its opposite sides to the bars 8 as at 11, and is provided at the sides of its inner end with slots 12 in which are slidably mounted bolts 80 13, to the outer ends of which are pivotally secured the lower ends of links 14. The upper ends of the links 14 are pivotally secured to the members 8 as at 15.

Secured to each of the links 14 between 85 the ends thereof are bolts 16 and to each of the bolts 16 is attached one end of a stout contractile spring 17, the other ends of the springs being secured to fingers 18 on the bars 8. A tripper member 19 is pivotally 90 mounted at 20 on each of the bars 8 and extends forwardly and rearwardly from said pivot. The rearwardly extending portion of the member 19 is provided with a notch or shoulder 21 which is adapted to hook 95 over bolt 16 and maintain the bar 14 in the position shown in Fig. 1 and against the influence of spring 17.

A block 22 is secured to each of the side walls 2, for a purpose to be presently explained.

In operation, the device is normally in the position shown in Fig. 1. The operator pulls out on the board 9 as if it were a drawer, and after the device has been drawn forward fully, the front ends of trippers 19 are depressed which releases the springs 17 and the latter draw the links up to the position shown in Fig. 2, thereby raising the typewriter to position for use. The rear 110 end of the member 9 is thus brought above the blocks 22, and the board is moved back

slightly over these blocks which hold the board in raised position. To return the device to normal position, merely pull forward until member 9 is disengaged from blocks 22, then press down the rear end of the board until the bolts 16 are caught in notches 21, and then move the entire structure rearwardly into the desk.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What I claim as new and desire to secure by Letters Patent is:—

1. In a device of the class described, the combination of a desk, rollers mounted on said desk, a bar provided with a double channel, one of the channels of which is adapted to coöperate with said rollers, a movable support, a plurality of rollers mounted on said support and adapted to coöperate with the other channel of said bar, a typewriter support pivotally mounted on said movable support, and a spring for moving said typewriter support from one position to another.

2. In a device of the class described, the combination of a desk, rollers mounted on said desk, a bar provided with a double channel, one of the channels of which is adapted to coöperate with said rollers, a movable support, a plurality of rollers mounted on said support and adapted to coöperate with the other channel of said bar, a typewriter support pivotally mounted at one end on said movable support, a link connecting said movable support with the other end of said typewriter support, and a spring secured to said link for moving said typewriter support from one position to another.

3. In a device of the class described, the combination of a desk, rollers mounted on said desk, a bar provided with a double channel, one of the channels of which is

adapted to coöperate with said rollers, a movable support, a plurality of rollers mounted on said support and adapted to coöperate with the other channel of said bar, a typewriter support pivotally mounted at one end on said movable support, a link connecting said movable support with the other end of said typewriter support, a spring secured to said link for moving said typewriter support from one position to another, and means for rendering said spring ineffective.

4. In a device of the class described, the combination of a desk, rollers mounted on said desk, a bar provided with a double channel, one of the channels of which is adapted to coöperate with said rollers, a movable support, a plurality of rollers mounted on said support and adapted to coöperate with the other channel of said bar, a typewriter support pivotally mounted at one end on said movable support, a link connecting said movable support with the other end of said typewriter support, a spring secured to said link for moving said typewriter support from one position to another, and means for rendering said spring ineffective and effective.

5. In a device of the class described, the combination of a desk, rollers mounted on said desk, a bar provided with a double channel, one of the channels of which is adapted to coöperate with said rollers, a movable support, a plurality of rollers mounted on said support and adapted to coöperate with the other channel of said bar, a typewriter support pivotally mounted on said movable support, a link connecting said movable support with the other end of said typewriter support, a bolt secured to said link, a spring secured to said bolt and adapted to move said typewriter support from one position to another, and a member pivoted on said movable support and coöoperative with said bolt for controlling said spring.

In testimony whereof I have affixed my signature.

METHOLD F. SITTA.
